7 Claims. (Cl. 315—35)

In high speed printers and tape-punching machines utilizing electric spark generated shockwaves the individual spark gaps have to be arranged close to one another. In such a tape-punching machine one spark gap is required for each of the usually five to eight parallel code hole tracks. The spacing between the said tracks is usually approximately 2.5 mm. and the spark gaps must therefore also be spaced apart the same distance. In a high-speed printer utilizing spark generated shockwaves one spark gap is provided for each character printing area of a line. In this machine the spacing between the spark gaps is equal to the width of a character printing area, for example, from 2.5 mm. to 4 mm. To obtain a serviceable output the inductance in a spark discharge circuit must be as low as possible. Thus two important requirements are imposed upon such a group of spark gaps: small distance between the gaps and low inductances of the supply conductors. A further requirement is that the heat produced can be dissipated satisfactorily.

An object of the invention is to provide a device having a group of spark gaps which fulfills the above requirements due to the complete discharge circuit comprising the spark gaps, the discharge capacitors and the supply leads forming a unit.

It is known to build together a spark gap, discharge capacitor and supply conductors for producing electric sparks for lighting purposes. This known, however, comprises only a single spark gap of coaxial form. Such a coaxial form is unsuitable, however, for arranging a plurality of spark gaps close to one another since, with the comparatively small diameters than to be utilized, the necessary capacitance requires a great length of the coaxial capacitor (cylindrical capacitor). Furthermore an aperture must be provided through which the pressure wave which is building up cylindrically about the axis of the spark impinges substantially directly on the object (paper and matrice or character). This is difficult to realize with a coaxial form of the spark gap.

According to the invention in a device having closely adjacent spark gaps constituted by spark electrodes and separate igniting electrodes by the use of a block consisting of alternately dielectric layers and metal layers, the individual metal layers in each case constituting alternately the supply conductor to one spark electrode, which also serves as a capacitor electrode, and a further capacitor electrode which is directly connected to the other spark electrode of the spark gap.

In stacking, the sequence of the layers and plates is thus as follows: supply conductor to one electrode, insulation, supply conductor to the other electrode, insulation, etc. Preferably, the dielectric material used for the required insulating plates is such that the capacitance bridging a spark gap suffices for the capacitor to act as a supply capacitor for the electric spark. These capacitors, referred to as discharge capacitors, are comparatively cheap to manufacture for the envisaged purpose.

In order that the invention may be readily carried into effect, two embodiments thereof will now be described in detail, by way of example, with reference to the accompanying drawings.

FIG. 1 is a perspective view of one embodiment of a

2

multi-electric spark discharge block of a high speed printer according to the invention.

FIG. 2 is a diagrammatic view of the circuit of the discharge block according to the invention.

5 FIG. 3 is another perspective view of a different embodiment of a discharge block according to the invention.

An assembly according to the invention comprises a plurality of spark gaps including electrodes, supply conductors and capacitors, which assembly is referred to hereinafter as the discharge block. A simple embodiment

10 of a discharge block is the open structure shown in FIG. 1. In this embodiment, for example, n spark gaps (only three are shown) are defined by each pair of spark electrodes A_1-K_1 , A_2-K_2 , etc. to A_n-K_n . Each spark gap

15 defining a pair of electrodes having associate therewith an igniting electrode Z_1 , Z_2 , etc. to Z_n . The electrodes A_1 to A_n , all of which have the same potential, are placed in a copper block 1 which represents the point O in the circuit diagram shown in FIG. 2. The opposing spark

20 electrodes K_1 to K_n are soldered to copper plates 2', 2'', etc., which serve as supply conductors and also as large area contacts with one of the capacitor electrodes, C_{a1} , C_{b1} , etc., said copper plates 2 being connected to

25 points c_1 to c_n respectively in the circuit diagram of FIG.

2. The electrodes A_1 to A_n are arranged opposite to the electrodes K_1 to K_n . An insulating strip and spacer 3

29 separates the copper plates 2', 2'', etc., from the copper

30 block 1 and provides the necessary and proper spacing

35 between the electrodes A and K. The igniting electrodes Z_1 to Z_n are fixed in bores in the strip 3.

Between each two adjacent copper plates 2, 2'', etc.,

34 connected to the spark electrodes K_2 and K_3 , for example

35 plates 2'' and 2''', there are arranged two dielectric plates

4, 4' for example ceramic plates, which are separated by

36 a further copper plate 5. All the copper plates 5 are con-

37 nected to the copper block 1, as may be seen from the

38 copper plates 5' and 5'' (which is broken away). Each of

39 the plates 5 forms a large area contact with the other

40 electrode of one of the capacitors C_{a1} , C_{b1} to C_{an} , C_{bn}

41 and a supply conductor to one of the electrodes A_1 to A_n

42 (FIG. 2).

43 Between each two adjacent copper plates 2, 2'', etc.,

44 connected to the spark electrodes K_2 and K_3 , for example

45 plates 2'' and 2''', there are arranged two dielectric plates

4, 4' for example ceramic plates, which are separated by

46 a further copper plate 5. All the copper plates 5 are con-

47 nected to the copper block 1, as may be seen from the

48 copper plates 5' and 5'' (which is broken away). Each of

49 the plates 5 forms a large area contact with the other

50 electrode of one of the capacitors C_{a1} , C_{b1} to C_{an} , C_{bn}

51 and a supply conductor to one of the electrodes A_1 to A_n

52 (FIG. 2).

53 The capacitor electrodes 5 themselves are metal layers

54 provided in the usual manner on the dielectric plates 4,

55 which metal layers must not extend, at least on the upper

56 side in FIG. 1, as far as the edges of the plates 4 in order

57 to obtain adequate insulation. To ensure good passage

58 of the spark current it is advantageous to solder the said

59 metal layers 5 to the copper block 1. The plates 5 are

60 made as thin as possible to permit a substantial number

61 to be used for storage of dielectric charge.

62 The stack comprising the plurality of copper plates

63 2 and 5 and the dielectric plates 4 in each case begins and

64 terminates with a plate 5. Thus two capacitors, each sep-

65 arated by a dielectric plate, are connected in parallel with

66 each spark gap. So the volume of two dielectric stored

67 plates is available as the dielectric charge volume for

68 each spark gap.

69 The maximum storage of electrical energy is obtained

70 if the dielectric is charged to its maximum permissible

71 field strength. For all the capacitors of the discharge

72 block the length of the spark gaps and the distances from

73 spark gap to spark gap are predetermined. Thus the

74 maximum operating voltage and the maximum operating

75 field strength are also determined. The material for the

76 dielectric plates 4 is chosen as a function of the maximum

77 operating field strength. To obtain optimum conditions

78 it may sometimes be useful to employ different dielectrics.

79 With discharge blocks intended for strip-punching

80 machines and high speed printers the operating field

81 strength occurring is usually comparatively low. Ceramic

material having a high dielectric constant is therefore especially suitable for the dielectric plates.

The complete discharge block consisting of capacitors C_{a1} , C_{b1} to C_{an} , C_{bn} is resiliently clamped together for absorbing electrostrictive variations in thickness of the dielectric plates which occur under certain conditions. For this purpose, clamping bolts 7 are passed through the bores in terminal plates 6 and press on these terminal plates from the outside with the interposition of suitable springs (not shown). Since the location of the desired action of the gaps A, K is determined during punching by the position of the punching matrices and during printing by the positions of the characters the very small shifts of the spark gaps caused by a possible electrostriction are not troublesome.

A second embodiment, shown in FIG. 3, is especially suitable for higher powers. In this embodiment the complete discharge block consisting of a plurality of capacitors is incorporated in a metal holder 8 closed on all sides and filled with oil. The necessary insulating distances with respect to the open structure FIG. 1, are thus smaller. The dissipation of heat becomes very favorable and may still be improved by providing cooling fins on the holder 8 or, more effectively still, by circulation of the oil from holder 8 through a cooler. The embodiment shown in FIG. 3 has 8 spark gaps, such as may be used, for example, for a machine for punching code holes in tape. In this case the spark gaps are formed, as surface-spark gaps. A copper block 9 to which the electrodes A are soldered constitutes part of the wall of the holder 8. An insulator 10 is provided in the wall of the holder 8 also to allow the passage of the electrodes K and the igniting electrodes Z. Material especially suitable for the insulator is ceramic material, which can be soldered to the holder, for example of copper, in a liquid-tight manner and with good thermal contact.

The circuit of the embodiment shown in FIG. 3 is the same as that shown in FIG. 2 for the discharge block of open structure shown in FIG. 1. The connections of the igniting electrodes Z and the connections c made to the plates 2 are led to the exterior, for example, through ceramic lead-through devices 11 and 12 respectively which have been closed by soldering. The connection O is the housing 8 itself. Side plates 13 merely serve for mounting of the device.

What is claimed is:

1. A multiple spark printer comprising means defining a plurality of spark gaps, each said spark gap including a pair of spark electrodes in spaced opposed relation, capacitor means coupled with each said pair of spark electrodes; said capacitor means comprising a first capacitor electrode sandwiched between a pair of dielectric members, said first capacitor electrode being connected with one said spark

electrode, and a second capacitor electrode on each said dielectric member remote from said first capacitor electrode, said second capacitor electrode being connected with the other of said spark electrodes, and lead-in conductor means coupled with said capacitor electrodes.

2. A multiple spark printer according to claim 1 wherein said first and second capacitor electrodes comprise thin films of conductive material attached to said dielectric members.

3. A multiple spark printer according to claim 2 wherein said capacitor means coupled with each said pair of electrodes have different dielectric values.

4. A multiple spark printer according to claim 2 with the addition of means for resiliently clamping together said capacitor means for each said spark gap.

5. A multiple spark printer according to claim 1 wherein in said means defining a plurality of spark gaps comprises, a bar of conductive material having a plurality of spark electrodes projecting therefrom in the same direction in spaced parallel relation, said bar being connected with one of said first and second capacitor electrodes, and an insulator-spacer member extending parallel with said projecting spark electrodes for separating said bar from said capacitor means and the associated spark electrodes thereof, one said lead-in conductor means being coupled with said bar.

6. A multiple spark printer according to claim 1 with the addition of housing means of conductive material enclosing said capacitor means coupled with one of said first and second capacitor electrodes.

7. A multiple spark printer according to claim 6 wherein in said means defining a plurality of spark gaps comprises said housing means; said housing means having a wall member including a first plurality of surface electrodes integral therewith and connected through said housing means with one said lead-in conductor, an insulator means in said wall member adjacent said surface electrodes, and a second plurality of surface electrodes in said insulator means in spaced opposed relation with said first plurality of electrodes, and means for connecting the other of said first and second capacitor electrodes.
